UNITED STATES PATENT OFFICE.

WALTER F. TROTTER, OF CHARLESTON, WEST VIRGINIA, ASSIGNOR TO THE JEFFREY MANUFACTURING COMPANY, A CORPORATION OF OHIO.

ELECTRICALLY-DRIVEN DRILL.

1,086,797.

Specification of Letters Patent.

Patented Feb. 10, 1914.

Application filed December 31, 1907. Serial No. 408,756.

To all whom it may concern:

Be it known that I, WALTER F. TROTTER, citizen of the United States, residing at Charleston, in the county of Kanawha and

5 State of West Virginia, have invented certain new and useful Improvements in Electrically-Driven Drills, of which the following is a specification, reference being had therein to the accompanying drawing.

10 This invention relates to electrically driven mining machines and more especially to drills such as are used in coal mines for boring holes to receive explosive charges and for other purposes.

15 The object of this invention is to provide a drill of the class specified having improved means of power transmission, improved means of feeding, and such other improvements as are evident from the following specification.

20 In some mines explosive gases are met with and serious explosions result if there be any exposed flame or sparks in the region where such gases collect. As is well known, the direct current motors commonly used in driving drills frequently cause sparks and flames of such nature that explosive gases of the kind found in these mines will be fired. I, therefore, prefer to 25 inclose all of the electrical parts of my drill in such a way that any sparks which may form cannot be communicated to the external atmosphere.

25 In the accompanying drawings in which is illustrated a practical embodiment of my improvements, Figure 1 is a perspective view of the drill and its support. Fig. 2 is a vertical longitudinal section through the drill, with the feed screw omitted. Fig. 3 is 30 a rear end elevation of the drill. Figs. 4 and 5 are side and end elevations of the feed nut detached and shown on an enlarged scale.

35 I have shown my improved drill supported upon an adjustable frame A adapted to engage the floor and roof of the mine and provide a firm support. The motor B has its field frame 1, provided on either side with trunnions 2 which are pivotally supported in the sliding blocks or clamps A', 40 which engage the channel side bars A'' of the supporting frame. With this construction the motor may swing about a horizontal axis, may be raised or lowered

and the frame as a whole is capable of swinging bodily upon a vertical axis, thus 55 providing a universally adjustable support for the drill.

The field frame 1 carries the poles 3-4, with the usual windings at 3'-4'. The armature 5 is mounted upon a hollow shaft 6 which has supporting bearings at 7-8, mounted in end plates 9 and 10, of the motor frame. These end plates are bolted to the sides or edges of the field frame in a manner to tightly inclose the field and armature. The plate 10 is formed with an extension or off-set 10^a to receive the commutator 21 and brushes 22 which are mounted upon insulating blocks 23 on the inner wall of the extension 10^a. Into the front end of 70 the shaft 6 is threaded the pinion 11. This pinion meshes with upper and lower spur gears 12 which are fast on shafts 13. These shafts 13 have bearing supports at 13^a in the end plate 9, and at 13^b in the plate 14^a 75 which forms one side of a gear casing 14, this gear casing being preferably cast in one with the plate 9, as shown. Each of the shafts 13 carries a pinion 15 and these pinions mesh with the spur gear 16 rigidly 80 mounted on the sleeve 17. This sleeve has a long bearing support in the extension 18 of the plate 14^a. The drill screw 20 is mounted in the hollow shaft 6 and the sleeve 17 and is adapted to be rotated by the ribs 85 or splines 17^a of the sleeve 17 which slidingly engage the grooves 20^a of the screw. At its front end the screw carries a drill bit as 24 and at its rear end I provide a handle 68. 90

The feeding device is designated as an entirety by 25. This feeding device is of the type shown and described in my pending application for a patent, filed September 7, 1906, Ser. No. 333,697. As my present 95 invention relates in part to improvements in feeding devices of this character, I will, therefore, describe in detail the feeding mechanism.

26 is a shell bolted upon the shouldered end 18^a of the extension 18 and having mounted upon its forward reduced end thrust collars 27 and ball cage 28 of the thrust bearing.

29 is a casing mounted upon the front 100 of the shell 26 and having a cover 30 screwed

into its front end. The cover 30 has a laterally extending boss 30^a which is bored out to receive the pin 31.

The feed nut proper, 32, comprising the two semi-cylindrical sections is arranged in front of the cover 30 and is held rigidly in position by the casing 33. This casing is made up of an upper part 34 and a lower part 35 which are formed with hollow bosses 34^a—35^a to receive bosses 32^a which project from the respective sections of the nut 32. Screw bolts 36 and 37 are threaded into the bosses 32^a and assist in securing the feed nut and casing rigidly together. The upper and lower sections 34—35 of the casing are provided on one side with hinge lugs 34^b and 35^b which are pivotally mounted on the pin 31 carried by the bearing casing cover 30. On their opposite sides the casing sections 34—35 are provided with clamping lugs, those at 34^c on the upper section carrying the eye-bolt 38 which has its nut 39 in engagement with the lower side of the lugs 35^c on the lower section of the casing. Each of these sections is formed at its rear end with an out-turned flange, which flanges abut the casing cover 30 and which are provided at one side with the fingers or lugs 34^d—35^d which are designed to embrace the cylindrical boss 30^b carried by the cover 30.

It will be seen that with the construction provided, the feed nut together with its casing 33 is, so far as rotational movement is concerned, rigid with the casing 29—30 of the thrust bearing. To prevent the rotation of these parts the casing member 29 is grooved at 29^a to receive a friction band 40, which is provided with clamping lugs 40^a which carry a clamping bolt 41. On the side opposite the clamping bolt, the friction band is provided with a laterally projecting lug 40^b designed to engage an abutment 42 which is bolted to the shell 26. It is clear that the clamping action of the band 40 may be varied by adjusting the tension on the bolt 41, so that the feed nut may be locked rigidly against rotation or may be permitted to have a slow rotation corresponding to the slippage between the friction band 40 and the casing 29.

At the commutator end of the armature shaft, I provide a collar 45 which is provided with internal splines 45^a to engage the grooves of the drill screw and which is centrally supported by the casing shell 46 secured to the casing part 10^a. This collar helps to properly support the drill screw and to prevent its coming in contact with the rapidly rotating armature shaft 6.

I have already pointed out that the end plates 9 and 10 in connection with the field frame form a casing which tightly incloses the field, armature, commutator and brushes. In this way these parts are rendered flame proof, that is to say, they are so thoroughly

inclosed that any flame due to sparking or arcing within the casing can not pass to the outside of the casing to ignite any explosive gases that might be present in the surrounding atmosphere.

47 designates as an entirety the combined starting box and connection box. That which I prefer and have shown in the drawings is similar to that shown and described in the pending application of Frank L. Sessions, filed February 18th, 1908, Ser. No. 416,546. This starting and connection box is entirely inclosed by the flame proof casing 48 and is attached to the motor frame by means of the screws 49^a.

57 represents the operating lever, by means of which the motor is started. As shown in Fig. 3, this operating lever is at the "On" position and is held in place by the spring catch 58. When this catch 58 is released, the operating lever 57 will move automatically to the "Off" position.

47^a are plug openings adapted to receive the supply circuit terminals and are so constructed that the terminals may be inserted or removed without any sparks being communicated to the external atmosphere.

In the operation of my improved drill, its supporting frame A is first clamped in a suitable position between the floor and roof of the mine and the motor is adjusted to the desired height. Then by grasping the handle 68 on the rear end of the drill screw, the latter may be swung to the desired angle. The terminal sockets of the supply conductors are now inserted to engage the motor terminals and the starting handle moved to the "On" position. The rotation of the armature is transmitted through the reducing gearing consisting of the pinion 11, spur gears 12, pinions 15 and spur gear 16 to the sleeve 17, which in turn rotates the feed screw. If now the friction band 40 is tight enough to prevent rotation of the feed nut, the drill will be fed forward in its rotation at the maximum rate. But if there is slippage between the friction band and the feed nut, the rate of feed will be proportionally diminished. Furthermore, if the drill strikes exceptionally hard material slippage may occur at the friction band and thus breakage of some of the parts which might otherwise occur is obviated.

If explosive gases are present in the mine in which the machine is being used there is little or no danger of explosions occurring by reason of the flame proof construction which has been set forth.

What I claim is:

1. In an electric coal and rock drill, the combination of the motor housing, the motor shaft, detachable end walls for the housing, one of the said end walls being formed inwardly at its center to provide a tubular support for the motor shaft bearing, the

- outer edges of the said end wall flanged outwardly in the form of a casing, the cover for the casing separable on lines parallel to the axis of the shaft, the tubular extension 5 formed at the center of the said cover, the drill shaft journaled in the said tubular extension, and the drill feeding devices secured on the outer end of the said tubular extension.
2. In an electric coal and rock drill, the combination of the motor housing, the motor shaft, detachable end walls for the housing, one of the said end walls being formed inwardly at its center to provide a tubular 15 support for the motor shaft bearings, the outer edges of said end wall flanged outward to provide a gear casing, the drill shaft and gears intermediate the motor shaft and drill shaft and contained entirely within the said casing.
3. In an electric coal or rock drill, the combination of the motor shaft, the motor housing, the detachable end walls of the said housing, one of the said end walls being 25 formed inwardly at its center to provide a motor shaft bearing support, the outer edges of the said end wall flanged outwardly in the form of a casing, the cover for the casing separable on lines parallel to the axis 30 of the shaft, the drill shaft journaled in the said casing cover, and the intermediate gear-

ing contained within the casing, the said gearing transmitting power from the motor shaft to the drill shaft.

4. In an electric coal or rock drill, the combination of the motor shaft, the field frame, the end walls detachably secured to the field frame and inclosing the motor, one of the said end walls formed inwardly at its center to provide a support for the motor 40 shaft bearing, the outer edges of the said end wall formed outwardly away from the motor to provide a gear casing, the drill shaft, the cover for the casing provided with a bearing in which the said drill shaft rotates, said cover being separable along lines parallel to the axis of the drill shaft, the pinion carried by the end of the motor shaft, the gear carried by the drill shaft at its end adjacent the motor shaft, the intermediate 45 gears connecting the said pinion and gear, the shafts carrying the said intermediate gears, and bearings provided in the said detachable end wall and casing cover for the said intermediate gearing shafts. 50

In testimony whereof I affix my signature, in presence of two witnesses.

WALTER F. TROTTER.
